ture, showing my new design but shown separately to reveal aspects of the design that may not be apparent in other views;

FIG. 21 is a front, right, isometric view thereof; FIG. 22 is a front elevation view thereof, the rear elevation view is identical;

FIG. 23 is a left side elevation view thereof;

FIG. 24 is a right side elevation view thereof;

FIG. 25 is a top plan view thereof;

FIG. 26 is a bottom plan view thereof;

FIG. 27 is a front, right, isometric view of FIG. 20 in the bent state, shown separately to reveal aspects of the design that may not be apparent in other views;

FIG. 28 is a top isometric view of the fifth component making up a set of reconfigurable kids furniture, showing my new design, but shown separately to reveal aspects of the design that may not be apparent in other views;

FIG. 29 is a front elevation view thereof, the rear elevation view is identical;

FIG. 30 is a left side elevation view thereof, the right side elevation view is identical;

FIG. 31 is a top plan view thereof;

FIG. 32 is a bottom plan view thereof;

FIG. 33 is a front isometric view of a first configuration, consisting of a combination of the five components previously shown separately;

FIG. 34 is a front isometric view of the second configuration, consisting of a combination of the five components previously shown separately;

FIG. 35 is a front isometric view of the third configuration, consisting of a combination of the five components previously shown separately;

FIG. 36 is a front isometric view of the fourth configuration, consisting of a combination of the five components previously shown separately;

FIG. 37 is a front isometric view of the fifth configuration, consisting of a combination of the five components previously shown separately;

FIG. 38 is a front isometric view of the sixth configuration, consisting of a combination of the five components previously shown separately;

FIG. 39 is a front isometric view of the seventh configuration, consisting of a combination of the five components previously shown separately;

FIG. 40 is a front isometric view of the eighth configuration, consisting of a combination of the five components previously shown separately;

FIG. 41 is a front isometric view of the ninth configuration, consisting of a combination of the five components previously shown separately;

FIG. 42 is a front isometric view of the tenth configuration, consisting of a combination of the five components previously shown separately;

FIG. 43 is a front isometric view of the eleventh configuration, consisting of a combination of the five components previously shown separately; and,

FIG. 44 is a front isometric view of the twelfth configuration, consisting of a combination of the five components previously shown separately.
